FLIER FOR TEXTILE MACHINES

Walter Hartley, Radcliffe, England

Application October 14, 1949, Serial No. 121,243
In Great Britain May 28, 1949

1 Claim. (Cl. 57—115)

1

This invention relates to flyers for textile machines such as roving frames, spinning frames and like machines of the general type in which the legs, tubes or barrels of the flyer are connected at the top by a transverse member which in turn is fixed to a central tubular driving socket. The upper portion of the socket has one or more side holes, and the fibrous material coming from the front delivery rollers of the machine passes through the central bore of the socket downwards and then through one of the said side holes to the top of one of the flyer legs, then through or around the leg downwards and finally, either directly through an eye or bush in the lower end of the leg, or over a radially pivoted presser arm and an eye at the end of the arm, onto a bobbin which is located on the driving spindle.

When present forms of flyer are used in the conventional arrangement of spindle, flyer and bobbin for the twisting and packaging of the fibrous strand or roving emerging from the front delivery rollers, it is frequently found that the twist inserted in the said strand or roving is so distributed over the length of roving between the delivery rollers and the bobbin that the portion of the roving that is passing between the delivery rollers and the flyer socket is insufficiently twisted and consequently not strong enough to withstand the strains imposed upon it. Breakages occur in the aforesaid portion of the roving, leading to the making of waste and stoppages of the machine to enable the piecing up operation to be performed. Another disadvantage is that a large number of fibres tend to become detached from the aforesaid portion of the roving and accumulate in the form of "fly" on the machine, necessitating frequent cleaning operations on the part of the machine attendant.

The present invention has for its object the provision of an improvement in the flyer whereby the foregoing disadvantages are substantially eliminated or minimised, and better packages are wound which in turn lead to better results in subsequent operations.

I have found that the said disadvantages of the present forms of flyer can be substantially overcome by means of an improvement that ensures that more of the total amount of twist that is inserted in the roving is put into the portion between the front delivery rollers and the top of the flyer, but without increasing said total amount of twist. I have found that this improvement impedes or delays the running out of twist from the said portion of the roving between the de-

livery rollers and the flyer top, and that this leads to a strengthening of the said portion and a reduction in breakages; furthermore, the fibres of the roving are more tightly bound together in the portion where they are most likely to become detached.

In order to attain this condition the invention provides within the central bore of the flyer socket, and diametrically mounted therein or thereon, a device in the form of a plate having therein an opening through which the roving is passed before it proceeds out through one of the rove holes, the top edge of the plate having a rounded external surface in simulation of the top of a mule spindle, more of the twist than hitherto being inserted by the use of such device in the roving between the flyer socket and the nip of the front delivery rollers.

The invention is more particularly set forth with reference to the accompanying drawings in which:

Fig. 1 is a front elevation of a flyer showing the invention.

Fig. 2 is a side elevation partly in section.

Fig. 3 is a front elevation of the inserted part which is shown in dotted lines in Fig. 1.

The flyer, which follows the usual construction in its main features, has a socket 6 by which it is mounted on the spindle, a hollow leg 7 and a balancing leg 8, the socket 6 has one or more rove holes 9, two being usual, as shown.

Inside the top part of the socket 6, diametrically mounted is a device or fitting 12 through or under which the roving 10, travelling in the direction of the arrows, is passed as it is brought down through the open top of the socket to pass out through one of the rove holes 9, on its way to the hollow leg whence it passes to the paddle 11 and the bobbin (not shown in the drawings) on which the package is built.

The device or fitting 12 is in the form of a small plate shown alone at Fig. 3 having a hole 13 in the middle which in the construction shown is somewhat of pear shape. This plate 12 is mounted in the socket 6 and across the axis on which the flyer rotates and the roving 10 passes through the hole 13 on its way to the rove hole 9. The important feature of this device is not so much the shape of the hole 13 as the top of the device indicated at 14 under which the roving must pass: if desired, for instance the hole 13 could be more in the nature of a vertical slot open at the bottom.

The top external edge of the device is provided with a tip 16 at the centre, to approximate to

the tip of a mule spindle round which the roving slips.

I claim:

In a socketed flyer for textile spinning machines, a plate disposed diametrically within the central bore of the flyer socket, said plate having an opening at its center portion through which the roving is passed before it passes out of the socket, the top edge of said plate being externally rounded at central portion thereof thereby to impart to the roving a greater degree of twist as it passes from the flyer socket.

WALTER HARTLEY.
